UNITED STATES PATENT OFFICE.

FREDERIC R. C. BOYD, OF BOSTON, MASSACHUSETTS, AND CYRUS HOWARD HAPGOOD, OF NUTLEY, NEW JERSEY, ASSIGNEES TO THE DE LAVAL SEPARATOR COMPANY, OF NEW YORK, N. Y., A CORPORATION OF NEW JERSEY.

LUBRICATING-OIL PURIFYING AND RECLAIMING SYSTEM.

1,363,833.

Specification of Letters Patent. Patented Dec. 28, 1920.

Application filed February 27, 1920. Serial No. 361,872.

To all whom it may concern:

Be it known that we, FREDERIC R. C. BOYD and CYRUS HOWARD HAPGOOD, citizens of the United States, residing at, respectively, 5 Boston, county of Suffolk, State of Massachusetts, and Nutley, county of Essex, and State of New Jersey, have invented a new and useful Improvement in Lubricating-Oil Purifying and Reclaiming Systems, of 10 which the following is a full, clear, and exact description, reference being had to the accompanying drawings, which form a part of this specification.

The lubricating oil purifying and re- 15 claiming system set forth in the Kennedy Patent No. 1,318,086, dated October 7, 1919, is also stated to be especially applicable to sea going ships, although it is stated that it may be found applicable to other lubricat- 20 ing systems. The system has, in fact, been found to be adaptable to power generators other than marine engines and particularly to turbine driven electric generators. In fact, the specific embodiment of the invention de- 25 scribed and illustrated in the Kennedy patent may be, without modification, applied to the lubricating systems of electric generating plants, and give much better re- 30 sults than are attainable with the filtration systems generally employed. However, the application, to a turbine driven electric generator, of the specific system disclosed by Kennedy as illustrative of his invention, may involve considerable modification of the 35 oiling system now in use, thereby making the installation relatively expensive. Moreover, a purchaser who is not absolutely convinced of the superiority of the Kennedy system may hesitate to make a change 40 which, if it should prove relatively unsatisfactory, might necessitate a restoration of the original system at considerable expense. These considerations militate against sales 45 of a system having the specific construction best designed for marine use.

The object of the present invention is so to modify the marine system of purifying and reclaiming oil as to better adapt it to land use, and especially to power driven 50 electric generators.

These electric generating plants vary widely in size, and while the main features of the present invention are applicable to

large and small generating plants, different specific constructions are best adapted to the 55 large and small plants respectively. We have therefore disclosed two embodiments of our invention. It will be understood, however, that still other modifications may be devised that will involve no departure 60 from the principles underlying the invention.

In the drawings:

Figure 1 is a diagram of an oil purifying and reclaiming system adapted more especially to relatively large turbine driven electric generators. 65

Fig. 2 is a diagram of a system adaptable to a turbine driven electric generator where the construction of Fig. 1 cannot be readily 70 applied.

Referring first to the construction of Fig. 1: *a* represents a steam turbine and *b* an electric generator connected therewith. The base of the engine is shown hollowed out to 75 form an oil reservoir *c*. It should be understood, however, that machines of this type are generally already provided with an oil reservoir, and it is intended to utilize the usual oil reservoir, however it may be constructed or positioned. From this reservoir a pump *d* forces lubricating oil through a pipe *e*, connections therefrom to the several bearings being shown at *f*, *g* and *h*. The oil escaping from the several bearings passes 80 down pipes *i*, *j*, and *k* to the oil reservoir. The described means for conveying oil to and from the bearings is typical, although it will be understood that other arrangements are available and any arrangement 85 already in use in any given plant may be left undisturbed. A pipe *m*, equipped with a relief valve *n*, leads from pipe *e* to the reservoir. Through this pipe passes oil pumped from the reservoir in excess of that 90 which flows through the bearings. 95

From the reservoir *c* extends a discharge pipe *o*. This pipe is preferably so located that it takes out oil from the lowest level of the reservoir, where the oil is most contaminated with water or dirt or both. The pipe *o* is of goose-neck shape, its discharge end being at the level of the oil in the reservoir. The pipe *o* discharges into a funnel *p* communicating with a pipe *r* leading to a 100 centrifugal separator and purifier *t*, which 105

is preferably of the type shown in the Kennedy patent aforesaid. A valve *s* on pipe *r* regulates the flow of oil to the separator.

The separator and purifier *t* removes the 5 oil, dirt and other impurities from the oil. The pure oil flows into a tank *u*. A pump *v* conveys the purified oil through a pipe *w* back to the tank *c*. The separator and purifier *t* and the pump *v* may be driven from a 10 common driving shaft or motor, or independently, as desired.

A pipe *x* extends from the tank *u* into the reservoir *c* and opens somewhat above the normal level of the oil therein. It is normally functionless, but if an abnormal quantity of oil is introduced into the reservoir, 15 some of the excess will be carried off by the pipe *x* into the tank *u*.

A pipe *y*, provided with a normally closed 20 valve *z*, extends from the lower part of pipe *o* to the pipe *r*.

The system described may be used in different ways. It is usually preferred to allow a continuous flow of oil from the reservoir to the separator and purifier, the purified oil being continuously pumped from the tank *u* to the reservoir *c*. This may be called the "continuous system" of cleaning. If, however, it is desired to clean the entire 25 volume of oil at intervals, valve *z* may be opened when the machine is shut down and all the oil in the reservoir *c* may be allowed to pass through pipes *y* and *r* to the separator and purifier, the tank *u* being made of sufficient capacity to hold all the oil 30 discharged from the reservoir, the pump *v*, being shut down. After swabbing out the reservoir *c*, pump *v* will be started and the reservoir filled with clean oil. This may be 35 called the "batch system" of cleaning. Both the "continuous system" and the "batch system" may be employed.

It should be noted that in the continuous system no oil is positively withdrawn from 40 the system, such dirty oil as flows to the purifier being only such as has been displaced by clean oil added.

In the construction shown in Fig. 2, the following elements are illustrated having 45 the same construction and arrangement as in Fig. 1, and are similarly lettered: turbine *a*, generator *b*, reservoir *c*, pump *d*, pipe *e*, branches *f*, *g* and *h* to bearings, and pipes *i*, *j* and *k* discharging from bearings 50 to reservoir.

A pipe *l* extends from pipe *e* to a pipe 55 11, which is connected with an overhead settling tank 16 to receive the overflow therefrom and convey it to the reservoir *c*. From between the ends of pipe *l*, a pipe 60 12 extends to the inflow of the settling tank 16. Between pipes 11 and 12 pipe *l* is provided with a normally closed valve 13. A relief valve is positioned either on pipe 65 10, as indicated at 14, or on pipe 12 at its

discharge end, as indicated at 15, or at any point along pipe 12. The relief valve so functions that any oil in excess of that taken by the bearings will be pumped to the settling tank, from there overflowing through 70 pipe 11 back to the reservoir *c*. Water, dirt and the like settle to the bottom of the tank 16 and thence pass, through pipe 17, to the centrifugal separator and purifier 18. The pure oil discharged therefrom is transferred, 75 through pipe 19, to the reservoir. For convenience of illustration, the pipe 19 is shown as connected to pipe 11.

In this system, also, the separator and purifier may be, if desired, cut out of the 80 circuit and the oil allowed to circulate endlessly from the reservoir to the bearings and back again. If it is further desired to cut out not only the purifier, but also the overhead settling tank, valve 13 may be opened 85 to allow the excess oil to pass through pipes 10 and 11 direct to the reservoir. The purifier and separator may be again placed in the oil circulating system by closing the valve 13. 90

Where, in the claims, we specify an engine, we mean to be understood as using the word in its broad sense and as comprehending, for example, an electric generator and its driving turbine. 95

Having now fully described our invention, what we claim and desire to protect by Letters Patent is:

1. In a lubricating oil purifying and reclaiming apparatus, the combination with 100 the engine, of an endless oiling system comprising a receptacle adapted to receive oil drained from the engine bearings and pipe connections through which oil may be pumped from the receptacle direct to the 105 engine bearings, a centrifugal separator and purifier adapted to remove impurities from the oil, and automatically operating means to divert excess oil from the system and convey it to the separator and purifier. 110

2. In a lubricating oil purifying and reclaiming apparatus, the combination with the engine, of an endless oiling system comprising a receptacle adapted to receive oil drained from the engine bearings and pipe 115 connections through which oil may be pumped from the receptacle direct to the engine bearings, a centrifugal separator and purifier adapted to remove impurities from the oil, automatically operating means to 120 divert excess oil from the system and convey it to the separator and purifier, and means to return the oil so purified to the endless system.

3. In a lubricating oil purifying and reclaiming apparatus, the combination with the engine having a series of bearings, of an oil supply pipe communicating directly with the several bearings, a pump for lifting oil from the receptacle directly to the 130

- supply pipe, means whereby oil drained from the bearings is conveyed to the receptacle, and a centrifugal separator and purifier connected with the oiling system and adapted to receive therefrom oil and remove its impurities, and means to convey the purified oil back to the system. 5
4. In a lubricating oil purifying and reclaiming apparatus, the combination with the engine, of an endless oiling system comprising a receptacle adapted to receive oil drained from the engine bearings and pipe connections through which oil may be pumped from the receptacle to the engine 10 bearings; a by-passage connected with said pipe connections and said receptacle and adapted to by-pass oil around the bearings and back to the receptacle, and a relief valve in said passage, and a centrifugal 15 separator and purifier connected with the oiling system and adapted to receive therefrom oil and remove its impurities, and means to convey the purified oil back to the system. 20
5. In a lubricating oil purifying and reclaiming apparatus, the combination with the engine, of an endless oiling system comprising a receptacle adapted to receive oil drained from the engine bearings and pipe 25 connections through which oil may be pumped from the receptacle to the engine bearings, a centrifugal separator and purifier adapted to remove the impurities from the oil, and means, inoperative when the 30 system contains only a given quantity of oil, but operative when the quantity of oil in the system exceeds said given quantity, to displace oil from the system and conduct it to said separator and purifier. 35
6. In a lubricating oil purifying and reclaiming apparatus, the combination with the engine, of an endless oiling system comprising a receptacle adapted to receive oil drained from the engine bearings and pipe 40 connections through which oil may be pumped from the receptacle to the engine bearings, a centrifugal separator and purifier adapted to remove the impurities from the oil, means, inoperative when the system contains only a given quantity of oil, but operative when the quantity of oil in the system exceeds said given quantity, to displace oil from the system and conduct it to said separator and purifier, and means to return the 45 oil so purified to the endless system. 50
7. In a lubricating oil purifying and reclaiming apparatus, the combination with the engine, of an endless oiling system comprising a receptacle adapted to receive oil 55 drained from the engine bearings and pipe connections through which oil may be pumped from the receptacle to the engine bearings, a centrifugal separator and purifier adapted to remove impurities from the oil, and overflow means adapted, when the 60
- level of the oil in the receptacle rises above a predetermined level, to carry off oil from the receptacle and convey it to the separator and purifier. 65
8. In a lubricating oil purifying and reclaiming apparatus, the combination with the engine, of an endless oiling system comprising a receptacle adapted to receive oil drained from the engine bearings and pipe connections through which oil may be pumped from the receptacle to the engine bearings, a centrifugal separator and purifier adapted to remove impurities from the oil, overflow means adapted, when the level of the oil in the receptacle rises above a predetermined level, to carry off oil from the receptacle and convey it to the separator and purifier, and means to return the oil so purified to the endless system. 70
9. In a lubricating oil purifying and reclaiming apparatus, the combination with the engine, of an endless oiling system comprising a receptacle adapted to receive oil drained from the engine bearings and pipe connections through which oil may be pumped from the receptacle to the engine bearings; a centrifugal purifier and separator arranged below said receptacle, pipe connection from said receptacle to the purifier and separator, a second receptacle adapted to receive purified oil from the purifier and separator, a pipe connection from the second receptacle to the first receptacle and a pump to force oil from the second receptacle through the last named pipe connection to the first receptacle. 75
10. In a lubricating oil purifying and reclaiming apparatus, the combination with the engine, of an endless oiling system comprising a receptacle adapted to receive oil drained from the engine bearings and pipe connections through which oil may be pumped from the receptacle to the engine bearings; a by-pass from said pipe connections direct to the receptacle and a relief valve thereon, a centrifugal purifier and separator arranged below said receptacle, pipe connection from said receptacle to the purifier and separator, a second receptacle adapted to receive purified oil from the purifier and separator, a pipe connection from the second receptacle to the first receptacle and a pump to force oil from the second receptacle through the last named pipe connection to the first receptacle. 80
11. In a lubricating oil purifying and reclaiming apparatus, the combination with the engine, of an endless oiling system comprising a receptacle adapted to receive oil drained from the engine bearings and pipe connections through which oil may be pumped from the receptacle to the engine bearings; a centrifugal purifier and separator arranged below said receptacle, a funnel positioned laterally of said receptacle, a 85
- 120
- 125
- 130

centrifugal separator and purifier arranged below said receptacle and funnel, a pipe connecting the funnel with the separator and purifier, a goose-neck pipe connecting the lower part of said receptacle with the funnel, and means to return the purified oil to the system.

In testimony of which invention, we have hereunto set our hands, respectively, at Boston, Massachusetts, and Philadelphia, Pennsylvania, on the 21st day of February, 1920, and the 24th day of January, 1920.

FREDERIC R. C. BOYD.
CYRUS HOWARD HAPGOOD.
